INKLE LOOM

Secondo B. Strona, 2525 Mountain Drive,
Upland, Calif. 91786

Filed Dec. 2, 1971, Ser. No. 204,391

Term of patent 14 years

Int. Cl. D15—06

U.S. Cl. D92—15

FIG. 1 is a perspective view of an inkle loom showing my new design;

FIG. 2 is a side elevation, taken in the direction of the arrow 2 in FIG. 1;

FIG. 3 is a top plan view;

FIG. 4 is an end elevational view, taken from the right end in FIG. 1; and

FIG. 5 is a bottom plan view.

I claim:

The ornamental design for an inkle loom, as shown.
